UNITED STATES PATENT OFFICE

JAMES H. GRAHAME, OF PORT ARTHUR, TEXAS, ASSIGNOR TO THE TEXAS COMPANY,
OF NEW YORK, N. Y., A CORPORATION OF DELAWARE

METHOD OF AND APPARATUS FOR DISTILLATION OF HYDROCARBON OILS

Application filed April 24, 1930. Serial No. 446,829.

This invention relates to an improved method of and apparatus for the distillation of hydrocarbon oils and more particularly to the treatment of hydrocarbon oils for the 5 production of vapor and liquid fractions which are to undergo further treatment.

Broadly, the invention contemplates the treatment of hydrocarbons oils for the production of vapor and liquid fractions which 10 comprises heating the oil, subjecting the heated oil to vaporizing conditions wherein it disposed in a shallow film-like body from which a vaporous fraction is evolved and a liquid fraction remains, subjecting the 15 evolved vapors to scrubbing action wherein the vapor together with such liquid particles as are entrained therewith are caused to flow at varying velocity and with abrupt directional changes in flow with the vaporizer, introducing a gas to the liquid fraction to strip 20 out desirable low boiling constituents remaining admixed therewith and subsequently commingling them with the evolved vapor fraction which is being scrubbed, removing 25 the scrubbed vapors and withdrawing the liquid fraction substantially free from desired low boiling constituents.

In the distillation of hydrocarbon oils as 25 commonly practiced with conventional pipe still apparatus a stream of oil to be treated is passed through a heating coil where it is heated to a predetermined temperature following which it may be delivered to a vaporizer or to the vaporizing section of a dephlegmator or fractionator wherein the low boiling or volatile constituents are evolved as a vapor and separated from the unvaporized or high boiling liquid portion and subsequently subjected to dephlegmation while 40 the liquid portion may be withdrawn from the system to storage or for further treatment.

In operations of this nature difficulty may 45 frequently be experienced in effectively flashing or vaporizing the desired low boiling constituents from a liquid which is undergoing treatment particularly where this liquid is maintained in relatively deep pools during the vaporization of the low boiling 50 components such that an appreciable liquid

head or static pressure must be overcome by the vapor rising towards the surface from within the liquid body, thereby necessitating maintaining relatively high temperatures and/or employing a relatively large quantity 55 of steam in order to facilitate vaporization and completely strip out the desired constituents.

Furthermore, the evolved vapors during separation from the liquid portion, usually 60 entrain and carry along with them appreciable amounts of undesired liquid material in the form of finely suspended mist-like particles, the entrainment of which is further enhanced through the necessary use of relatively large amounts of steam introduced 65 into and contacted with the main body of vaporizing liquid to effectively strip out the low boiling constituents as previously mentioned. 70

For example, in the conventional distillation of a relatively high boiling hydrocarbon oil such as a reduced or topped crude, from which the gasoline and kerosene fractions have been removed, for the production of a 75 distillate cylinder oil fraction and a residual liquid fraction which may be of the nature of a residuum or heavy fuel oil it is difficult to completely and effectively separate all of the desired cylinder stock constituents from the residual fuel fraction while on the other hand the vaporized portion may contain a considerable quantity of fuel residuum entrained in a fine suspension, the presence of which is undesirable in the resulting cylinder oil distillate since it may result in a final product having an excessively high content 80 of residual carbonaceous matter.

The present invention therefore contemplates passing oil through a heating coil 90 wherein it may be heated to a predetermined temperature corresponding to the vaporizing temperature of certain of its desirable lighter fractions, introducing the heated oil tangentially in a plurality of streams to a vaporizer or flash tower wherein the streams of fluid delivered at a relatively high linear velocity are jettied against an inner surface thereof over which they are distributed to form a shallow film or sheet of liquid from which, 95 100

due to the extremely small liquid head, the low boiling constituents or desirable lighter fractions are readily flashed into vapor leaving an unvaporized liquid portion to collect in the bottom of the vaporizer. This liquid portion may be contacted with a gas or steam to strip out any desirable low boiling constituents which may have been unintentionally deposited therewith. The combined vapors including steam used for this final stripping are passed through a plurality of successive scrubbing stages within the vaporizer wherein the combined vapors flow through a region or zone of progressively enlarging cross sectional area in which the linear velocity of flow gradually decreases to thereby facilitate precipitation and deposition of entrained liquid particles, then flow through a succeeding zone of progressively decreasing cross sectional area wherein the linear velocity of flow gradually increases. The vapors are deflected and their direction of flow is abruptly reversed while moving at a high velocity to effect further separation and precipitation of entrained particles as the result of the whirling action during reversal of flow. The scrubbed vapors substantially free from entrained matter may then be conducted to a refractionator while the excess high boiling liquid collecting in the lower portion of the flash tower may be withdrawn from the system.

Another important aspect of the invention contemplates an improved apparatus suitable for practicing the invention.

In order to more fully disclose the invention, reference will now be made to the figures of the accompanying drawings illustrating diagrammatically a preferred embodiment of the apparatus adapted to carrying out the invention in which:

Figure 1 is a diagrammatic view, partially in section, of the vaporizer.

Figure 2 is a horizontal cross sectional view taken on the line 2-2 of Figure 1.

Figure 3 illustrates diagrammatically a section of peripheral openings and baffles in the inner chambers of the vaporizer shown in Figures 1 and 2.

Figure 4 is a flow diagram illustrating a preferred arrangement of apparatus adapted to carry out the method of the invention.

Referring to Figures 1, 2, and 3, the vaporizer comprises a vertical vessel 1, the outer surface of which is preferably covered with heat insulating material 1a having a plurality of inlet nozzles or pipes 3a, 3b, etc., tangentially connected with respect to the inner surface of the circular shell of the vessel.

Eccentric cylindrical chambers 4 and 5, preferably of progressively decreasing diameter, are placed within the vessel 1 and preferably depend from its top 6, making a solid or vapor proof joint therewith, while their

lower and free ends project towards the bottom of the vessel and are adapted to submerge beneath the surface of a body of liquid 1b maintained within the bottom of the vessel. These eccentric chambers may be braced together by suitable spacers or bracket members 7 and while only two eccentric chambers are thus described, it is contemplated that any desired number of such chambers may be placed within the vessel.

Panel sections 8 and 9 each having a series of baffled vertical openings 10 are provided in suitable openings in the walls of the chambers 4 and 5 respectively, affording means of vapor communication between the chambers, each panel or section being designed and disposed in the wall of its respective chamber so as to cause the vapors to flow substantially completely around the periphery or outside of each chamber before gaining access to its interior.

As illustrated in Figure 3, each of the panels 8 and 9 comprise a plurality of flat vertical vanes or baffles 9a, 9b, etc., spaced a suitable distance apart by means of spacers 10a, 10b, etc., to form narrow vertical apertures or openings. The inner vertical edges of the vanes may be slightly inclined towards each other, the amount of such inclination depending more or less upon the width of the baffles as well as the number of baffled openings employed in a given section. In addition all of the vanes in each panel are set angularly with respect to the periphery of the chamber so as to impart a whirling or rotary motion to the vapors as they flow around the outer vertical edges of the vanes or baffles and enter the openings there between and as a result of which their direction of flow is reversed forcing them to flow substantially completely around the exterior of the next and inner chamber in a direction exactly the reverse of that followed about the outer surface of the preceding chamber before reaching the panel section of the inner chamber whereupon they are again subjected to a similar whirling movement with a subsequent reversal in direction of flow.

Any desired number of these peripheral openings may be employed and they may be arranged individually rather than in sections comprising a series of openings. Preferably these openings in the wall of each chamber occupy different elevations thereby causing the vapors to follow an up and down course in flowing from one chamber to the next as the case may be as an additional means of facilitating removal of entrained matter.

A vapor outlet 11 is provided in the top of the innermost chamber 5 through which the final scrubbed vapors are withdrawn to be conducted, preferably, to a dephlegmator as will be described later in connection with the discussion of Figure 4.

A liquid outlet 12, having a valve 13, is

70

130

provided at the bottom of the vessel 1 through which liquid collecting in the bottom thereof may be disposed of in any suitable manner. The valve 13 is preferably controlled automatically by a float 14 located within the vessel and adapted to maintain therein a suitable depth of liquid so that the lower, and otherwise open, ends of the inner chambers 4 and 5 are constantly submerged beneath the surface of the liquid to afford a seal and thereby prevent vapor flowing around the lower edges of the chambers rather than entirely through their peripheral openings as described above.

15 A suitable steam spray 15 is located within the bottom of the vessel 1 preferably well submerged below the surface of the body of liquid maintained therein through which steam may be admitted and caused to commingle or contact with the liquid as it bubbles therethrough in order to facilitate vaporization and strip out desirable low boiling constituents remaining dissolved in or admixed with the liquid.

20 25 A hood or baffle 4a supported by straps 4b depending from the lower edge of the chamber 4 serves to divert the vapors released from the liquid in the bottom of the vaporizer due to the admission of steam thereto into the space surrounding the chamber 4 wherein it combines with the main vapor fraction for removal of entrained matter.

In the treatment of hydrocarbon oil where-
30 35 in a desired fraction is evolved which is to undergo subsequent rectification as will now be described in connection with Figure 4, a pump 23 withdraws oil from a storage tank 20, through a line 21, having a valve 22, and delivers it through a line 24 to a heating coil 25, preferably a conventional pipe still heater wherein the oil may be heated under confining spatial conditions and without substantial vaporization of its low
40 45 boiling constituents following which it is introduced tangentially through the inlet pipes 3a, 3b, etc., having valves 3x, 3y, etc., into the interior of the vessel 1. These inlet pipes serve to jet the oil at a relatively high velocity against the inner surface of the vessel over which it spreads to form a shallow vertical sheet or film of fluid from which the desired low boiling constituents are evolved as a vapor and the remaining un-
50 55 vaporized liquid fraction is deposited to collect in the bottom of the vessel.

The evolved vapors flow through the space between the inner surface of the vessel 1 and the exterior of the chamber 4 and in doing so pass first through a region of progressively increasing cross sectional area, corresponding to the gradually widening portion of the annular space between the wall of the vessel 1 and that of the chamber 4 eccentrically positioned therewithin, wherein the vapor ve-

locity proportionally decreases to facilitate deposition of the entrained material, and then through a region of progressively decreasing cross-sectional area, wherein the vapor velocity proportionally increases, following which the direction of vapor flow is reversed as it passes through the peripheral openings in the panel 8. The vertical vanes or baffles 9a, 9b, etc., impart a rotary or whirling motion to the vapors as they enter the openings between the vanes thereby bringing about a further separation of the entrained material which is precipitated outwards by centrifugal force and either deposited on that portion of the inner surface of the vessel or chamber adjacent to the panel section, or drops directly to the bottom of the vessel to commingle with the liquid fraction collecting therein.

Upon passing through the peripheral openings 10 and gaining access to the interior of the chamber 4 the vapors again pass through the same series of successive variations in flow to reach the interior of the next inner chamber 5.

Accordingly it is seen that the vapors flowing from one chamber to the next go through a gradual swelling in which the volume of the vapor increases to a maximum with a corresponding decrease in linear velocity of flow then through a gradual contraction in which the volume decreases to a minimum with a corresponding increase in linear velocity whereupon its direction of flow is completely reversed.

The entrained matter separated from the vapors during their passage around and through the cylindrical chambers is deposited directly in the bottom of the vessel or is precipitated against the surfaces of the outer vessel and its inner chambers to trickle down to the bottom of the vessel and admix with the unvaporized liquid collecting therein, the excess of which may be withdrawn through the pipe 12, having a valve 13, to a cooling coil 28 from which it is conducted through a line 29 to storage or for disposition in some other suitable manner.

The final scrubbed vapor is removed through the vapor line 11 and may be conducted to a dephlegmator 30 wherein it is subjected to fractionation to form one or more final products such as, for example, a fractionated vapor which may be passed through a line 31 and final condenser 32 to form a distillate which is withdrawn to storage through a pipe 33, and a liquid fraction which may be withdrawn from the bottom of the dephlegmator through a line 35 to storage.

Steam may be admitted to the bottom of the vessel 1 through a pipe 16 and the spray 15 within the bottom of the vessel and thereby contacted with the liquid surrounding the spray or spider to strip out light constituents

remaining in this liquid. Steam introduced for this purpose together with the light material which it has stripped out of the liquid mixes or commingles with the main vapor 5 fraction which is being scrubbed in the upper portion of the vaporizer as already described.

While provision has thus been provided for the admission and use of steam or gas, it is contemplated that in many instances its use 10 may be unnecessary since sufficient stripping or separation of the low boiling materials will be effected during the separation of vapor immediately following distribution of the heated oil charge in the form of a liquid 15 sheet within the vaporizer shell.

Although substantially atmospheric pressures are usually employed in conventional pipe still vaporization it is to be understood that the vaporizer described above may be 20 equally well adapted to withstand either sub-atmospheric or super-atmospheric pressures.

Obviously many modifications and variations of the invention, as hereinbefore set forth, may be made without departing from 25 the spirit and scope thereof, and therefore, only such limitations should be imposed as are indicated in the appended claims.

I claim:

1. A method of treating hydrocarbon oil 30 comprising heating the oil to the vaporizing temperature of certain of its desirable lighter fractions, introducing the heated oil into an enlarged vessel, disposing the oil in a film therein to thereby facilitate the vaporization of the said lighter fractions, depositing an unvaporized portion of the oil in the bottom of the vessel, moving a vaporized fraction and such liquid particles as are entrained therewith through a passage first 35 of increasing and then of decreasing cross-sectional area thus varying the velocity of the vaporous fraction, abruptly changing the direction of flow of the vaporous fraction while flowing at the higher velocity and successively 40 repeating the movement to thereby mechanically remove the entrained liquid particles, eventually releasing the substantially liquid free vaporous fraction overhead to further treating means while regulatably 45 withdrawing the surplus of the unvaporized portion collecting in the bottom of the vessel.

2. A method of treating hydrocarbon oil comprising heating the oil to the vaporizing temperature of certain of its desirable lighter 50 fractions, introducing the heated oil into an enlarged vessel, disposing the oil in a film therein to thereby facilitate the vaporization of the said lighter fractions, depositing the unvaporized portion of the oil in the bottom 55 of the vessel, moving a vaporized fraction and such liquid particles as are entrained therewith through a passage first of increasing and then of decreasing cross-sectional area thus varying the velocity of the vaporous 60 fraction, abruptly changing the direction of 65

flow of the vaporous fraction while flowing at the higher velocity and repeating the movement to thereby mechanically remove the entrained liquid particles, eventually releasing the substantially liquid free vaporous fraction overhead to further treating means, introducing gas into the lower portion of the body of liquid deposited in the bottom of the vessel to thereby aid in vaporizing such unvaporized portions of the desirable lighter fraction as may have been unintentionally deposited with the liquid while regulatably withdrawing the surplus of the unvaporized portion collecting in the bottom of the vessel. 70 75

3. A method of treating hydrocarbon oil comprising heating the oil to the vaporizing temperature of certain of its desirable lighter fractions, introducing the heated oil into an enlarged vessel, disposing the oil in a film therein to thereby facilitate the vaporization of the said lighter fractions, depositing the unvaporized portion of the oil in the bottom of the vessel, moving a vaporous fraction and such liquid particles as are entrained therewith through a passage first of increasing and then of decreasing cross-sectional area thus varying the velocity of the vaporous fraction, abruptly changing the direction of flow of the vaporous fraction while flowing at the higher velocity and repeating the movement to thereby mechanically remove the entrained liquid particles, eventually releasing the substantially liquid free vaporous fraction overhead to further treating means, introducing gas into the lower portion of the body of liquid deposited in the bottom of the vessel to thereby aid in vaporizing such unvaporized portions of the desirable lighter fraction as may have been unintentionally deposited with the liquid, diverting the thus released vaporous fraction to the first mentioned passage of the vaporous fraction in the removal of entrained liquid while regulatably withdrawing the surplus of the unvaporized portion collecting in the bottom of the vessel. 80 85 90 95 100 105 110 115

4. In the treatment of hydrocarbon oil to form vapor and liquid fractions the method which comprises introducing a plurality of streams of heated oil to a vaporizer wherein a vaporous fraction is evolved and a liquid fraction is deposited in the bottom of the vaporizer, passing the evolved vapor through a plurality of successive scrubbing stages within the vaporizer in each of which the vapors flow through a zone of progressively decreasing vapor velocity then through a succeeding zone of progressively increasing vapor velocity whereupon their direction of flow is reversed to precipitate entrained matter therefrom, removing the scrubbed vapors for further treatment, depositing the precipitating entrained matter from the vapors in the bottom of the vaporizer to collect with the liquid fraction and regulatably with- 120 125

drawing the said liquid from the bottom of the vaporizer.

5. In the treatment of hydrocarbon oil to form vapor and liquid fractions the method which comprises introducing oil to a vaporizer wherein a vaporous fraction is evolved and a liquid fraction is deposited in the bottom of the vaporizer, passing the evolved vapor through a plurality of successive scrubbing stages within the vaporizer in each of which the vapors flow through a zone of progressively decreasing velocity then through a succeeding zone of progressively increasing velocity whereupon their direction of flow is reversed to precipitate entrained matter therefrom, removing the scrubbed vapors, depositing the precipitating entrained matter in the bottom of the vaporizer to collect with the liquid fraction, maintaining a body of the liquid within the vaporizer, introducing steam to the liquid body to strip out low boiling constituents remaining admixed therewith and regulatably withdrawing the excess of said liquid from the vaporizer.

6. In a vaporizer for separating more volatile fractions from less volatile fractions of hydrocarbon oil the combination which comprises a vessel having inlet ports through which the oil is introduced to the vessel whose lower portion is adapted to contain a body of liquid, a plurality of chambers one within the other and within the vessel disposed eccentrically therein with respect to the vessel and to each other, having their top ends integral with the top of the vessel while their bottom and open ends are adapted to project below the surface of a body of liquid in the bottom of the vessel and about which the volatilized fractions are caused to flow at varying velocity to effect precipitation of entrained matter, openings in each chamber wall affording vapor communication therebetween and so disposed that the vapor is caused to flow substantially completely around each chamber before gaining access to its interior, vanes at each opening adapted to impart whirling motion to the vapors flowing therethrough whereby further portions of remaining entrained matter are precipitated from the vapor, a vapor outlet through which the final vapors are removed from the innermost chamber, means for admitting steam to the bottom of the vessel, a baffle depending below the submerged ends of said eccentric chambers to divert steam and accompanying vapors rising from the body of liquid into the space surrounding the outer eccentric chamber, a liquid drawoff in the bottom of the vessel and automatic means regulating the flow of liquid through said draw-off.

7. In a vaporizer for separating more volatile fractions from less volatile fractions of hydrocarbon oil the combination which comprises a vessel having inlet ports through

which the oil is introduced to the vessel whose lower portion is adapted to contain a body of liquid, a plurality of depending cylinders one within the other and within the vessel disposed therein eccentrically with respect to the vessel and to each other, having their upper ends solidly secured to the top of the vessel while their lower ends are adapted to project below the surface of a body of liquid in the bottom of the vessel and about which the volatilized fractions are caused to flow at varying velocity to effect precipitation of entrained matter, a plurality of openings in each cylinder wall affording vapor communication therebetween and so disposed that the vapor is caused to flow substantially completely around each cylinder before gaining access to its interior, vanes at each opening adapted to impart whirling motion to the vapors flowing therethrough whereby further portions of remaining entrained matter are precipitated from the vapor, a vapor outlet through which the final vapors are removed from the innermost cylinder and a liquid drawoff at the bottom of said vessel.

8. In a vaporizer for separating more volatile fractions from less volatile fractions of hydrocarbon oil the combination which comprises a vessel having inlet ports through which the oil is introduced to the vessel whose lower portion is adapted to contain a body of liquid, a plurality of depending cylinders one within the other and within the vessel disposed eccentrically with respect to the vessel and to each other, having their upper ends solidly secured to the top of the vessel while their lower ends are adapted to project below the surface of a body of liquid in the bottom of the vessel and about which the volatilized fractions are caused to flow at varying velocity to precipitate entrained matter, a section of baffled openings in each cylinder wall affording vapor communication therebetween and such that the vapor is caused to flow substantially completely around each cylinder in a reversed direction to that followed when flowing around the preceding chamber, a vapor outlet through which the final vapors are removed from the innermost cylinder, means for introducing steam to the bottom of the vessel, a baffle depending below the submerged ends of said eccentric cylinders to divert steam and accompanying vapors rising from the body of liquid into the space surrounding the outer eccentric cylinder, a liquid drawoff in the bottom of the vessel and automatic means regulating the flow of liquid through said drawoff.

9. In a vaporizer for separating more volatile fractions from less volatile fractions of hydrocarbon oil the combination which comprises a vessel whose lower portion is adapted to contain a body of liquid, means

for admitting the oil to the inner surface of the vessel to form therein a relatively thin sheet of liquid; a plurality of chambers of progressively decreasing diameter supported one within the other within the vessel with their upper ends closed while their lower ends are adapted to project below the surface of the liquid in the bottom of the vessel, openings in the wall of each chamber affording vapor communication therebetween and such that the vapor is caused to flow around each chamber in a reverse direction to that followed when flowing around the preceding chamber and during which flow entrained matter is precipitated, a vapor outlet through which the final vapors are removed from the innermost chamber and means for removing surplus liquid collecting in the bottom of the vessel.

20 In witness whereof I have hereunto set my hand this 27th day of March, 1930.

JAMES H. GRAHAME.
